SAFETY DEVICE FOR GAS RANGES, GAS BOILERS, ETC

Original Filed April 15, 1931

Fig. 2

UNITED STATES PATENT OFFICE

2,031,415

SAFETY DEVICE FOR GAS RANGES, GAS
BOILERS, ETC.

Willy Katz, New York, N. Y.

Continuation of application Serial No. 530,263,
April 15, 1931. This application August 12,
1933, Serial No. 684,908

1 Claim. (Cl. 158—117.1)

This invention relates to improvements in safety devices, particularly to an electrically controlled valve for gas stoves or the like gas consuming apparatus, as for instance disclosed in 5 my pending application, Serial Number 530,263, filed April 15, 1931, of which this application is a continuation and for which it is to be substituted.

It is the principal object of my invention to 10 provide a safety device in which the gas is ignited by means of a resistance and its supply is controlled by an electromagnetically operated valve ensuring the lighting of the gas and preventing any escape of gas when not ignited.

15 Another object of my invention is the provision of a safety device for gas stoves equipped with a thermostat of the bi-metallic type to keep the electromagnetically controlled valve open while the gas is ignited and to close the valve as soon as 20 the gas flame is extinguished.

Still another object of my invention is the provision of a safety device for gas stoves equipped with means to allow a mechanical operation of the opening and closing means for the electric 25 circuits, yet preventing accidental operation thereof.

A further object of my invention is the provision of mechanically operated contact means to 30 close the igniter circuit and open the gas supply valve to the burner and to open said circuit as soon as the gas has been ignited.

A still further object of my invention is the provision of a control system for the burners of 35 gas ranges or the like avoiding the use of pilot lights and positively preventing accidents by the escape of gas from an unlit stove permitting a manual operation of the circuit closers as well as their automatic closing and opening during the 40 operation of the stove.

45 These and other objects and advantages of my invention will become more fully known as the description thereof proceeds and will then be more specifically defined in the appended claim.

In the accompanying drawing forming a material part of this disclosure:

Fig. 1 is a sectional side elevation of a safety device for gas ranges constructed according to my invention.

Fig. 2 is an end view thereof.

50 Fig. 3 is a section on line III—III of Figure 2.

Fig. 4 is a detail view of a gas burner with a thermostat circuit closer.

As illustrated, a gas supply pipe 42 connected at its lower end with any gas supply pipe in the 55 usual manner is connected with a valve casing

48 at its upper end and the flow of the gas is controlled by the usual manually operated regulating valve 48.

The valve casing 48 is connected by a pipe stem 49 having an air vent 45 with the gas burner 41, while a nozzle 44 is screwed into valve casing and pipe stem.

Valve casing 48 and pipe 42 carry a casing 50 having sockets 20 and 51 formed therein, the former for the reception and guidance of a push button 1, while the latter is arranged in superposition on socket 20, and constitutes a dash-pot having an opening 52 in its front wall. The front end of the push button being concave will prevent an accidental operation of the same. 15

The rear end of push button 1 is equipped with a flange 53 adapted to engage a nose formed on a lever 4 intermediate its ends.

Lever 4 of insulating material is attached at its lower end to a shaft 56, and at its upper end has 20 connected thereto one end of a spring 24, the other end of which is connected to a peg on the inner wall of casing 50.

The lever 4 is also connected at its upper end by means of a link connection 54 with a piston 25 55 working in the dash pot 51.

The lower end of lever 4 is curved and carries a pawl 25 pressed by means of a spring 46 into engagement with the teeth of a comparatively large ratchet wheel 5 of non-conducting material 30 rotatably arranged on the insulated shaft 56 and provided at its front face with the pairwise arranged contact pieces 23 and 31 and 23'—31' respectively.

In front of wheel 5 shaft 56 carries a wheel 3 35 also of non-conducting material secured thereto and equipped with contact pieces 36, 37 on its front face.

Upon the rotation of wheel 5 by means of lever 4 its contact pieces 23 and 31 come into contact 40 with spring contacts 38 and 21 while contact pieces 36, 37 of wheel 3 must be of a size sufficient to bring them upon the rotation of wheel 3 by lever 4 into engagement with contact springs 22 and 2. 45

Contact 30 is connected by a conductor wire 26 to one pole 32 of a battery or plug socket of a source of electricity, while contact 21 is connected by a wire 39 to one end of a resistance coil 42, the other end of which is connected by means 50 of wire 40 to the other pole 33 of the battery or plug socket.

Contact 2 is connected by means of wire 26 to the binding post 28 of an electromagnet 6, the other binding post 29 of which is connected by 55

wires 27 and 43 to one pole 35 of a bi-metallic thermostat 14, the other pole 38 of which is connected by wires 34 and 27 to pole 33 of the battery or plug socket. A spring contact 15 on the thermostat 14 is normally held spaced from a contact piece 18 of the same near the pole 35 thereof.

The electromagnet 6 is arranged partly in valve casing 48 and partly in the movable metallic body 10 of valve 9, and a spring 10 rests at one end against the end of body 9 and at its other end against a lock nut 11 in casing 48 and is wound about electromagnet 6 although spaced therefrom.

A lock nut 7 on the screw 8 holds the electromagnet 6 in place while the movement of body 10 is cushioned by means of a spring 21' in body 10, between the core end 19 of the electromagnet and the end wall of the body 9.

It is the purpose of non-metallic wheel 5 to avoid permanent closure of the circuit through wires 26, 26' as in such case the circuit would be interrupted only through an accidental extinction of the flame which would set the thermostat out of commission, while wheel 5 enables an arbitrary shutting off of the gas by interrupting the circuit at will by means of wheel 5.

The device operates as follows:

When it is desired to start the stove or to ignite any burner thereof, the push button 1 is pushed inwardly to move lever 4 against the action of its spring 24, pawl 25 will turn wheel 5 to bring its contact pieces 23, 31 into engagement with spring contacts 30 and 21 respectively.

Simultaneously shaft 56 and wheel 3 thereon will turn to bring its contacts 36, 37 into engagement with spring contacts 22 and 2, and the following circuits will be closed:

The circuit in which the igniter 12 is located, cross wire 38, contact 2, contact 37, wheel 3, contact 38, spring contact 22, wire 26 to pole 32, battery, pole 33, wire 40 to igniter 12. The igniter is then made to glow to ignite the gas, and the gas flame will cause the operation of the thermostat for closing the thermostat switch. By the closing of the thermostat switch a circuit is closed from pole 35, across wire 43 and wire 27 to pole 28 of the electromagnet, pole 28 of same, wire 26, contact spring 21, contact 31, wheel 5, contact 23, contact spring 30, wire 26 to the pole 32, pole 32, wire 34 to pole 39 of thermostat.

The energization of the electromagnet will attract body 9 to open the gas valve and if now the gas supply is turned on by means of valve 18 the igniter will ignite the same.

If now spring 24 which through the rearward

motion of lever 4 has been tensioned, expands again, lever 4 will slowly return into its original position on account of the dash pot arrangement and turn wheel 3 to bring its contact pieces 36, 37 out of engagement with spring contacts 22 and 2 and open the igniter circuit.

If the gas supply is cut off or the flame of the burner for any reason is extinguished, the thermostat will cool off and open the circuit across the electromagnet and deenergize the same, so that springs 10 and 21' will return valve body 9 into its valve closing position by engagement with nozzle 44 to prevent the escape of gas.

The cycle of operations is then repeated by pushing button 1 inwardly in order to bring contacts 23' and 31' of wheel 5 and the contacts of wheel 3 again into circuit closing position as aforesaid.

It will be understood that I have described and shown the preferred form of my device only as one example of the many possible ways to practically construct my invention and that I may make such changes in its general arrangement and in the construction of the minor details thereof as come within the scope of the appended claims without departure from the spirit of my invention and the principles involved.

Having thus described my invention what I claim as new and desire to secure by Letters Patent is:

A safety device for gas stoves comprising a gas burner, an electromagnetically controlled cut-off valve controlling the supply of gas to said burner, an igniter, a circuit in which said igniter is located, a push button operating a spring controlled lever, contact wheels operated by said lever to close said igniter circuit to glow said igniter, the spring of said lever returning the same into its original position after each operation by said button, for opening the igniter circuit, a thermostat and a circuit in which said thermostat is located to be closed upon the closure of said igniter circuit to heat the thermostat by the heat developed by the glowing igniter upon the closure of its circuit by said lever operated contact wheels, an electromagnet in said thermostat circuit to be energized upon the closure of this circuit to open the valve for supplying gas to said burner, and to be de-energized upon the extinguishing of the burner flame and consequent cooling off of the thermostat, and springs for moving the valve mechanically into its gas supply cutting off position.

WILLY KATZ.
